UNITED STATES PATENT OFFICE.

HARRY KEMP, OF NEWTON, MASSACHUSETTS.

FEEDING MECHANISM FOR CARDING-MACHINES.

No. 866,726.

Specification of Letters Patent.

Patented Sept. 24, 1907.

Application filed August 22, 1904. Serial No. 221,597.

To all whom it may concern:

Be it known that I, HARRY KEMP, a citizen of the United States, and a resident of Newton, in the county of Middlesex and State of Massachusetts, have invented 5 new and useful Improvements in Feeding Mechanisms for Carding-Machines, of which the following is a specification.

My invention relates to feeding mechanisms for carding machines and consists in improvements in the controlling mechanism of geared travelers, such as shown 10 and described in the Letters Patent of the United States, No. 701,487, granted to me under date of June 13, 1902. In that patent, to which I have reference, the frame marked A represents the ordinary bridge 15 theretofore used in the construction of diagonal card feeds and the devices which embodied my aforesaid patented improvement were combined and designed for application to such existing frames or bridges, and while they were and are, entirely and satisfactorily oper- 20 ative, the forms necessary to adaptation to the existing frames, which had not been designed originally with a view to receiving such attachments as represented by said patented improvements, were not such as would commend them to the machine designer in- 25 tending to build a complete feed, with a frame properly designed and adapted to receive my said improvements. In my said patent the relationship of rolls D and stop or abutment 29 is explained in such detail that repetition is unnecessary. The abutment 29 of said patent 30 is shown as carried by a U-shaped or arched yoke 28 which extends over the web of the bridge A, and is part of or rigidly secured to the plate 24 which carries the rolls D. This yoke permitted the roll carrying plate to be attached to the frame A without any more 35 special work than that involved in cutting the slot 26 to admit the clamping bolt 25.

In the drawings hereto annexed I have shown my improvement on the construction of the roll-carrying plate shown in the said patent.

40 Figure 1 is an elevation of a feeding mechanism for carding machines embodying my improvements. Fig. 2 is a sectional plan of one end of the mechanism shown in Fig. 1 the upper portion thereof being broken away. Fig. 3 is a section on line 3-3 of Fig. 1. Fig. 4 is a 45 modification hereinafter described.

Having reference to the drawings,—A represents the bridge of my improved feed mechanism, and as in the patent above noted this bridge carries the guide rod B upon which is hung the carrier E, the latter being recip- 50 roated by chain D' so as to lay the sliver upon the aprons (not shown) as usual. The carrier E comprises the usual plate or rocker G carrying the feed rolls g and gears g', the latter alternately coöperating with rack K as in the mechanism of my said patent.

55 The sprockets D which support the belt or chain D' are themselves supported by brackets H herein shown

as fastened to the inner side of the bridge A by bolts h extending through longitudinal slots h² provided in the web of bridge A, thus making provision for varying or adjusting the region of movement of the carrier with 60 relation to the aprons (not shown).

My present improvement consists in making the bridge A with a second pair of slots h¹ parallel with slots h² and through which the abutments h⁶ project into the path of the lug g³ on rocker G. That is, the abutments 65 h⁶ are not only fixed each directly to the body of its respective bracket instead of to an arched arm projecting from the body of the bracket as heretofore, but each also projects through a slot in the bridge which is parallel with the adjacent slot h² so that when bolts h are 70 loosened and the brackets adjusted the abutments can move freely in their slots with the brackets. An additional advantage to this construction is that when lug g³ strikes either abutment the shock which tends to swing the bracket on its bolt h is not borne so much by 75 the bracket and its bolt h but mostly by the side of the abutment slot h⁴ and therefore the shock does not tend as heretofore to disturb the adjustment of the bracket H or of the abutment itself. In other words, the abutment h⁶ not only coöperates with lug g³ but also as- 80 sists in holding the brackets in place against the shocks to which they are subjected and the abutments themselves are therefore more rigid than heretofore. Moreover the abutments being fixed to the brackets, the relationship between each abutment and the axis of its 85 sprocket is not disturbed when the brackets are adjusted. These advantages I have found from practical experience to be of mechanical and structural importance, but of course while I much prefer to have the abutment perform the double function of a bracket support 90 and abutment and while this in practice is an important advantage, yet I do not mean to say that it is essential to my invention.

In the best form of my invention the brackets H are made each with a slot h⁸ opposite to and parallel with 95 the slots h⁴ in the bridge and the abutments project through these slots h⁸ and are clamped therein by nuts h¹⁰. This construction is provided because slivers of one size require one relationship between the abutments and the axes of their sprockets while with sliv- 100 ers of another size a slightly different relationship is required and thus by connecting each abutment with its bracket, it can be adjusted relatively to its sprocket as may be required. This capacity for adjustment can, however, be secured in other ways as for example, by 105 making each bracket with a lug h¹² (Fig. 4) projecting through its slot h⁴ and carrying at its outer end an adjustable screw h¹³ for engaging the lug g³.

I do not claim broadly means for adjusting the sprocket-supporting bracket without altering the ad- 110 justment of the stop relatively thereto, nor an adjustable bracket with a stop or abutment adjustably fixed

thereto, in combination with the bridge, since my said Patent No. 701,487 shows parts which in their functions and coöperative relationship are the same in these respects as the similar parts described hereinabove, but

5 What I do claim and desire to secure by Letters Patent is:

1. In a feed mechanism for carding machines, in combination, a carrier-supporting bridge made with a pair of longitudinal parallel slots; a bracket for supporting the sprocket or the like of the carrier-reciprocating devices, said bracket being provided with a rigid abutment projecting through one of the slots into the path of the carrier, and a bolt in the other slot for clamping the bracket to the bridge.
- 10 2. In a feed mechanism for carding machines, in combination, a carrier-supporting bridge made with a pair of longitudinal parallel slots; a bracket for supporting the sprocket or the like of the carrier-reciprocating devices, said bracket being made with a slot opposite to and parallel with one of the slots of the bridge; an abutment adjustably fixed in the slot of the bracket and projecting through the adjacent slot of the bridge into the path of the carrier, and a bolt in the other slot of the bridge for 15 clamping the bracket to the bridge.
- 20 3. In a feed mechanism for carding machines, in combination, a carrier-supporting bridge made with a longitudinal slot; a bracket for supporting the sprocket or the like of the carrier-reciprocating devices, said bracket being provided with an abutment projecting through the slot into the path of the carrier, and means for holding the bracket rigid with reference to the bridge.
- 25 4. In a feed mechanism for carding machines, in combination, a carrier-supporting bridge made with a longitudinal slot; a bracket for supporting the sprocket or the

like of the carrier-reciprocating devices, said bracket being provided with an abutment adjustably mounted upon the bracket and projecting through the slot into the path of the carrier, and means for holding the bracket rigid with reference to the bridge.

40

5. In a feed mechanism for carding machines, in combination a carrier-supporting bridge made with a longitudinal slot; a bracket for supporting the sprocket or the like of the carrier-reciprocating devices, said bracket being provided with an abutment projecting through the slot into 45 the path of the carrier, and means for holding the bracket rigid with reference to the bridge, with provision for adjusting the same longitudinally with reference to the bridge.

45

6. In a feed mechanism for carding machines, in combination, a carrier-supporting bridge, made with a pair of longitudinal parallel slots; a bracket for supporting the sprocket or the like of the carrier-reciprocating devices; an abutment adjustably fixed to said bracket and projecting through one of the slots of the bridge into the path 50 of the carrier, and a bolt in the other slot of the bridge for clamping the bracket to the bridge.

55

7. The combination of the frame, stands adjustable thereon, the driving-wheels or rolls, supported on said stands, the driving-band or chain supported on said rolls, the carrier or traveler, driven by said band or chain, the rack supported on said frame, the pivoted plate, feed or delivery-rolls carried by said plate, gears rotary with said feed-rolls and adapted to engage said rack, one at a time, and reversing stops, supported on said stands and adjustable with said driving-wheels or rolls.

60

65 Signed by me at Boston, Massachusetts, this seventeenth day of August, 1904.

HARRY KEMP.
